US0D1098684S

(12) **United States Design Patent** (10) **Patent No.:** **US D1,098,684 S**
(45) **Date of Patent:** **** Oct. 21, 2025**

(54) **SHOE**

(71) Applicant: **adidas AG**, Herzogenaurach (DE)

(72) Inventors: **Andreas Hierl**, Nuremberg (DE); **Rider Anthony Evans**, Nuremberg (DE)

(73) Assignee: **adidas AG**, Herzogenaurach (DE)

(**) Term: **15 Years**

(21) Appl. No.: **29/992,599**

(22) Filed: **Mar. 10, 2025**

Related U.S. Application Data

(63) Continuation of application No. 29/869,636, filed on Jan. 5, 2023, now Pat. No. Des. 1,065,806.

(57) **CLAIM**

The ornamental design for a shoe as shown and described.

DESCRIPTION

FIG. 1 is a side view of a shoe showing the claimed design; and,

FIG. 2 is an enlarged view of the portion surrounded by broken lines in FIG. 1.

The broken lines in the figures and the area outside the broken lines show portions of the shoe that form no part of the claimed design.

The figures show the claimed design in grayscale. No specific gray coloring shown is claimed.

1 Claim, 2 Drawing Sheets
